(57) **CLAIM**

The ornamental design for a detachable cross member for hair clipper guide attachment, as shown and described.

DESCRIPTION

FIG. 1 is a front side perspective view of a detachable cross member for hair clipper guide attachment of the instant invention.

FIG. 2 is a right side elevation view of the detachable cross member for hair clipper guide attachment of FIG. 1, the opposing view being a mirror image thereof.

FIG. 3 is a top plan view of the detachable cross member for hair clipper guide attachment of FIG. 1.

FIG. 4 is a bottom plan view of the detachable cross member for hair clipper guide attachment of FIG. 1.

FIG. 5 is a front elevation view of the detachable cross member for hair clipper guide attachment FIG. 1; and, FIG. 6 is a rear elevation view of the detachable cross member for hair clipper guide attachment of FIG. 1.
